UNITED STATES PATENT OFFICE.

WILLIAM E. CANEDY, OF ROCHESTER, MINNESOTA.

COMBINED ANVIL AND VISE.

SPECIFICATION forming part of Letters Patent No. 380,019, dated March 27, 1888.

Application filed September 7, 1885. Renewed September 12, 1887. Serial No. 249,531. (No model.)

To all whom it may concern:

Be it known that I, WILLIAM E. CANEDY, residing at Rochester, in the county of Olmsted and State of Minnesota, have invented 5 certain new and useful Improvements in an Anvil and Vise, of which the following is a specification, reference being had therein to the accompanying drawings.

This invention relates to an anvil and vise; 10 and it consists in the improved construction by which the two are secured together so as to be readily put into or out of working position.

The object of the invention is to produce a 15 vise which may be firmly secured to the anvil and quickly turned down out of the way, leaving the whole top of the anvil clear.

In the drawings, Figure 1 is a side elevation of anvil and vise attached, the anvil being attached to a bench. Fig. 2 is a longitudinal section of anvil and part of rear jaw of vise, the remainder of vise in elevation. Fig. 3 is a rear elevation, and Fig. 4 a perspective, of rear jaw of vise. Fig. 5 is an end view of anvil. 25

A indicates the anvil, having a screw-threaded hole, B, in the end opposite the horn.

C is a vise of ordinary construction in most respects. The rear jaw, D, has a screw-threaded 30 projection, E, on its rear face, which may be cast thereon. The vise-screw F passes through this projection.

The projection E has a number of raised lugs, e, on its rear end, which lugs serve to 35 prevent the nut H on the vise-screw from turning.

The anvil has a half-round or other groove, K, in the end, to which the vise is attached.

The jaw D has a similar groove, L, in appropriate position, so that when the vise is ap-

plied to the anvil and turned until the rear jaw rests snugly against the anvil, the two grooves will be opposite each other and form a hole or passage between the vise and anvil. A pin or key forced into this hole prevents 45 the vise from being turned or loosened from the anvil; but when it is desired to use the entire surface of the anvil this key can be withdrawn, and by moving the vise a quarter-turn of screw E the vise will lie horizontally across 50 the end of the anvil, and need not be further removed to give free access to the face of the anvil. The inserted key, added to the large screw, gives a connection between anvil and vise of great strength and stiffness, and one of 55 very easy and quick adjustment.

I claim—

1. The combination, with an anvil having a screw-threaded hole in one side, of a vise having an attached screw-threaded projection 60 which enters said hole in the anvil, substantially as described.

2. The combination, with an anvil having a screw-threaded hole therein, of a vise having an attached screw-threaded projection which 65 enters said hole, and a fastening-key in a passage between the anvil and vise, substantially as described.

3. In combination with a vise-jaw having projecting lugs e e, a vise-screw passing between said lugs, and a nut on the vise-screw resting between and against the lugs, as set forth. 70

In testimony whereof I affix my signature in presence of two witnesses.

WILLIAM E. CANEDY.
